JAMES M. OSGOOD, OF SOMERVILLE, MASSACHUSETTS.

Letters Patent No. 77,647, dated May 5, 1868.

IMPROVEMENT IN MACHINE FOR CASTING EYELETS.

The Schedule referred to in these Letters Patent and making part of the same.

Be it known that I, JAMES M. OSGOOD, of Somerville, in the county of Middlesex, and State of Massachusetts, have invented a new and useful Machine for Making Eyelets, of which the following is a full, clear, and exact description, reference being had to the accompanying drawings, making a part of this specification, in which—

Figure 1 represents a perspective view of a machine embodying my improvements.

Figure 2 is a vertical transverse section of the same.

Figure 3 is a vertical longitudinal section of the cylinder; and

Figure 4 is an enlarged sectional view, in detail.

Similar letters indicate like parts in the several figures.

The object of my invention is to produce eyelets of cast metal or composition, and to finish them by machinery, without any intermediate manipulation, by which they can be manufactured very cheaply, and with great rapidity.

The invention consists in the employment of a series of annular recesses formed on the surface of a rotating cylinder, in which recesses are fitted sliding tubes, that surround fixed cylindrical pins, thus forming circular spaces for the reception of molten metal properly conducted to the same. A reciprocating longitudinal motion is given to the said sliding tubes by means of cross-bars, to which they are attached, the ends of the said cross-bars fitting in cam-grooves formed on the inner sides of the cylinder-heads.

In connection with the above is a second cylinder, of suitable size, studded on its surface with projections, buttons, or headers, which correspond with the recesses in the first-named cylinder, and are made to come in contact with the projecting ends of the partly-formed eyelet, and finish the heads or projecting edges of the same.

Referring to the drawings, A represents the bed, on which are the standards A' A' that support the shaft a. On the shaft a is a hub, b, to which is attached a cylinder, B, by arms or other suitable connections. At each end of the cylinder B, and secured to the standards, is a circular disk, C C', provided each with a cam-groove, D, on the inner side.

In these cam-grooves are fitted the ends of a series of cross-bars, c c' c'' c''', extending through the cylinder, and parallel to the shaft a. To these cross-bars is secured a series of cylindrical tubes, f f, so arranged and operated by the motion of the said cross-bars in the cam-grooves, that, in certain positions of the cylinder B, during its rotation, the outer ends of the tubes f will be flush with the surface of the cylinder, and thence be withdrawn into the cylinder to the required depth of the eyelet to be formed.

d d represent cylindrical pins or rods, secured to the central shaft a, and passing through the tubes f to a point even with the surface of the cylinder B, and upon or over which the said tubes are caused to slide.

The shaft a extends outwards, and to its end is attached a pulley or wheel, by which the shaft may be rotated by any suitable power.

G represents a cylinder, provided on its surface with projections y, as shown in fig. 4, corresponding in number with the recesses in cylinder B, so that, during the rotation or revolution of the cylinder, every projection will come exactly opposite a corresponding recess, and press against the partially-projected end of the cast eyelet, so as to form the head or projecting edges of the same.

H represents a thick metal plate, covering a portion of the cylinder B, and secured at each end to the stationary disks C C'. On the under side of the plate H is formed a recess or space, i, constituting a chamber for the reception of the melted metal of which the eyelet is to be formed. The melted metal is conducted to the said chamber i by means of a tube, k, leading to the chamber or vessel M, in which the metal is melted.

N, fig. 1, represents a force-pump, for forcing air or steam through the tube P to the melting-vessel M, for the purpose of supplying additional pressure to the metal in its passage to the cylinder B, if found necessary.

Instead of a rotating cylinder, a level plate may be used, in which may be fitted stationary pins and sliding tubes, in recesses formed in the said plate, where a reciprocating motion may be employed, instead of a rotating motion, to operate the sliding tubes.

The operation is as follows:

The metal or composition, being melted in the vessel M, will pass through the tube *k* to the chamber *i*, covering a portion of the surface of cylinder B, the latter being duly rotated.

At this point the tubes *f f'*, &c., are withdrawn into the cylinder, to the required depth of the eyelet to be formed.

By the action of the cross-rods in the cam-groove, the tubes commence to withdraw as the recesses enter the chamber *i* at one side, as shown in fig. 4, so that, in their passage through the space formed by chamber *i*, the tubes will be suddenly retracted, and so create a vacuum, into which the melted metal is at once forced. As the cylinder continues its rotation, the recesses pass by the edges of the plate H, thus smoothing off the outer ends of the metal eyelets in the same. The partially-formed eyelets, retaining their position in the recesses, are carried around in the cylinder, becoming cooled in the mean time, until they approach the projections on the cylinder G, when the cam-groove commences to force out gradually the tubes *f*, which causes the now cooled metal to project sufficiently from the recesses to form the head of the eyelet. After passing this point, the cam is so formed as to throw out the tubes *f* to their fullest extent, and thus eject the completed eyelet from the cylinder. The tube *f* will remain in this position until it again enters the chamber *i*.

The cylinder may be made of any size required, and contain as many recesses as can properly accommodate the number of pins and sliding tubes to be operated.

If the melting-vessel M is made air-tight, the vacuum caused by the running out of the metal may be filled from the air-pump N, and additional pressure may be used by the same means, if found necessary, but, under ordinary circumstances, the metal will run freely into the chamber *i*.

The outer ends of the recesses in the cylinder B may be countersunk, to aid in forming the heads of the eyelets, if found necessary.

Having thus described my invention, what I claim as new, and desire to secure by Letters Patent, is—

1. Making eyelets from cast metal, by the means substantially as described.
2. The fixed pins or rods *d*, in combination with the sliding tubes *f*, as and for the purpose set forth.
3. The combination of the fixed pins or rods *d*, the sliding tubes *f*, and the cylinder B, as described.
4. The combination of the cross-bars *c*, the sliding tubes *f*, and the cam-plates or disks C C', as and for the purpose specified.
5. The cylinder G, provided with the projections *y*, as and for the purpose set forth.
6. The chamber *i*, formed in the plate H, in combination with the cylinder B, as described.
7. A cast-metal eyelet, constructed by the means substantially as above described.

In testimony whereof, I have signed my name to this specification in the presence of two subscribing witnesses.

JAMES M. OSGOOD.
